UNITED STATES PATENT OFFICE.

MORTIMER I. REYNOLDS, OF HEBRON, NEBRASKA.

DESIGN FOR A FASTENER FOR CHAIRS.

SPECIFICATION forming part of Design No. 33,528, dated November 6, 1900.

Application filed October 13, 1900. Serial No. 33,013. Term of patent 14 years.

To all whom it may concern:

Be it known that I, MORTIMER I. REYNOLDS, a citizen of the United States, residing at Hebron, in the county of Thayer and State of Nebraska, have invented and produced a new and original Design for a Fastener for Chairs, of which the following is a specification.

This invention relates to a design for a fastener for chairs, and the leading feature ¹⁰ thereof consists in the design forming the subject-matter of the accompanying illustrations, wherein—

Figure 1 is a top plan view of a fastener embodying the features of the design. Fig. 2 is ¹⁵ an edge elevation of the same.

The design is characterized by a body 1, having opposite side edges 2, which are tapered and beveled and merge into rounded

corners 3 at the broad end of the body. The broadened end of the body is formed with a ²⁰ concave recess 4 in the arc of a circle, and from the center thereof extends a triangular projection 5. In the body a circular opening 6 is formed.

Having thus described the invention, what ²⁵ is claimed as new is—

The design for a fastener for a chair, herein shown and described.

In testimony that I claim the foregoing as my own I have hereto affixed my signature in ³⁰ the presence of two witnesses.

MORTIMER I. REYNOLDS.

Witnesses:
